UNITED STATES PATENT OFFICE.

NEHEMIAH A. AMSTER, OF ROYERSFORD, PENNSYLVANIA.

DESIGN FOR A STOCKING-DARNER.

43,710.

Specification for Design.

Patented Mar. 18, 1913.

Application filed July 11, 1912. Serial No. 708,913. Term of patent 14 years.

To all whom it may concern:

Be it known that I, NEHEMIAH A. AMSTER, a citizen of the United States, residing at Royersford, county of Montgomery, and State of Pennsylvania, have invented a new, original, and ornamental Design for Stocking-Darners, of which the following is a specification, reference being had to the accompanying drawing, forming part thereof.

The figure is a perspective view of a stocking darning showing my new design.

I claim:

The ornamental design for a stocking darning, as shown.

NEHEMIAH A. AMSTER.

Witnesses:

JAMES T. SATCHELL,
J. LINWOOD EISENBERG.
